Attorney, Agent, or Firm—Young & Thompson

[57] CLAIM

The ornamental design for a shoe, substantially as shown and described.

DESCRIPTION

FIG. 1 is a top plan view of a shoe showing our new design, the bottom being substantially plain and unornamented;

FIG. 2 is a left side elevational view thereof;

FIG. 3 is a left rear perspective view thereof;

FIG. 4 is a right front perspective view thereof;

FIG. 5 is a bottom and right rear perspective view thereof;

FIG. 6 is a top plan view of a second embodiment of our new design of FIGS. 1-5;

FIG. 7 is a left side elevational view thereof;

FIG. 8 is a left rear perspective view thereof;

FIG. 9 is a right front perspective view thereof;

FIG. 10 is a bottom and right rear perspective view thereof.

FIG. 4

FIG. 5
